(57) **CLAIM**

The ornamental design for a foldable corrugated corner element, as shown and described.

DESCRIPTION

FIG. 1 is an upper, front, right isometric view of a foldable corrugated corner element in an unfolded configuration, showing our new design;

FIG. 2 is a lower, front, right isometric view of the foldable corrugated corner element in an unfolded configuration;

FIG. 3 is an upper, front, left isometric view of the foldable corrugated corner element in an unfolded configuration;

FIG. 4 is a lower, rear, left isometric view of the foldable corrugated corner element in an unfolded configuration;

FIG. 5 is a top view of the foldable corrugated corner element in an unfolded configuration;

FIG. 6 is a bottom view of the foldable corrugated corner element in an unfolded configuration;

FIG. 7 is a front view of the foldable corrugated corner element in an unfolded configuration;

FIG. 8 is a rear view of the foldable corrugated corner element in an unfolded configuration;

FIG. 9 is a right side view of a foldable corrugated corner element in an unfolded configuration, showing our new design;

FIG. 10 is a left side view of the foldable corrugated corner element in an unfolded configuration;

FIG. 11 is an upper, front, right isometric view of a foldable corrugated corner element in a folded configuration, showing our new design;

FIG. 12 is a lower, front, left isometric view of the foldable corrugated corner element in a folded configuration;

FIG. 13 is an upper, rear, right isometric view of the foldable corrugated corner element in a folded configuration;

FIG. 14 is an upper, rear, left isometric view of the foldable corrugated corner element in a folded configuration;

FIG. 15 is a lower, rear, right isometric view of the foldable corrugated corner element in a folded configuration;

FIG. 16 is a lower, rear, left isometric view of the foldable corrugated corner element in a folded configuration;

FIG. 17 is a top view of the foldable corrugated corner element in a folded configuration;

FIG. 18 is a bottom view of the foldable corrugated corner element in a folded configuration;

FIG. 19 is a front view of a foldable corrugated corner element in a folded configuration, showing our new design;

(Continued)

FIG. 20 is a rear view of the foldable corrugated corner element in a folded configuration;
 FIG. 21 is a right side view of the foldable corrugated corner element in a folded configuration; and,
 FIG. 22 is a left side view of the foldable corrugated corner element in a folded configuration.
